ABSTRACT OF THE DISCLOSURE

A collapsible ladder wherein the rungs are pivotally attached to the upright legs and are so deformed at their ends as to prevent them from swinging in one direction, and a releasable pivoted lug is provided on one rung to prevent all the rungs from swinging in the opposite direction when the ladder is in extended condition for use. To collapse the ladder into a narrow but slightly longer mass, the said lug is swung out of the way and one leg is moved longitudinally with respect to the other to swing the rungs said opposite direction and thus bring the legs into mutual contact.

The accompanying drawings illustrate embodiments of the invention, and, referring briefly to the drawings:

FIG. 1 is a front elevational view, with parts broken away and partly in section, of a novel collapsible ladder.

FIG. 2 is a fragmentary enlarged view, with parts broken away and partly in section, of the ladder in fully collapsed condition.

FIG. 3 is a sectional view taken on the line 3—3 of FIG. 1.

FIG. 4 is a sectional view taken on the line 4—4 of FIG. 1.

FIG. 5 is a sectional view taken on the line 5—5 of FIG. 1.

FIG. 6 is a perspective view of the rung which is provided with the pivoted stop or locking lug.

Referring in detail to the drawing, the numerals 10 and 11 designate the opposed upright legs of the ladder which, together with other parts described below, are preferably made of a light weight material such as aluminum or an alloy of aluminum. The legs are in the form of channel members, that is, substantially U-shaped in cross-section, being made up of the channel bases 12 and the opposed wings 13. The legs are positioned with the channel bases 12 on the outer side, that is, with the open channels facing toward each other.

A plurality of ladder rungs 14 are provided, spaced vertically equidistant. Each rung is roughly S-shaped, as shown, and includes a straight intermediate section or body portion 15 having at one end a downwardly extending deformation or nose 16 and at the other end an upward extension, deformation or nose 17, both noses being at right angles to the straight body portion 15.

At the junctions of the noses 16 and 17 with the ends of the straight body portion 15 of each rung, a pivot pin 18 extending through the rung and the channel wings 13 pivotally attaches the rung to the ladder legs 10 and 11. The outer edges 19 of the noses 16 and 17 contact the channel bases 12 when the ladder is in the extended condition shown in full lines in FIG. 1. It is thus obvious that, as so far described, the rungs are constrained against swinging in a clockwise direction, FIG. 1, but they are obviously free to swing in a counter-clockwise direction. FIG. 1 illustrates in phantom an intermediate position of the swinging of the rungs in the counter-clockwise direction.

In order to constrain the rungs from swinging in a counter-clockwise direction, FIG. 1, when the ladder is in extended condition for use, the following provision

2

is made. At least one rung 14a above the bottommost rung is preferably provided in the form of a channel member throughout its length; the upwardly extending nose of this rung is shown at 17a. The pivot pin 18 of this rung, at the junction of the nose 17a with its straight intermediate body portion, also passes through the wings 20 of the rung, as well as through the upper end or head of an elongated lug 21 which is thus pivotally suspended from the pin 18 between the wings 20. The length of this lug is such that, when freely suspended, its lower extremity contacts and registers upon the upper extremity of the nose 17 of the next lower rung 14, as seen in FIG. 1.

It is now obvious that with the lug 21 in the position thereof shown in FIG. 1, the rungs cannot be swung in a counter-clockwise direction, for if a force to do so is applied, the lowermost nose 17 will be blocked against counter-clockwise swinging by the obstruction provided by the leg. For in order to swing counter-clockwise, the said lower nose 17 must move through an arc which, at the beginning, slopes upward in a direction from right to left. But the lug cannot yield to such a force since it is blocked against longitudinal movement by its pivot pin 18. Thus the ladder is secure against collapsing when in the extended condition.

In order to collapse the ladder in the direction of the topmost curved arrows, FIG. 1, the lug 21 must first be swung to the left, in the direction of the bottommost curved arrows. The lug may then be swung into the channel of the rung 14a where it will be concealed, as shown in FIG. 2, and the two legs 10 and 11 may then be brought together with all the rungs registering between the wings 13 of the legs. When collapsed, the ladder has a greatly reduced width and a slightly increased length, as is obvious.

Although the rung 14a has been shown channel-shaped, it together with the other rungs need not necessarily be so in order to provide a collapsible ladder of the kind disclosed. It is so that the lug 21 may register within the channel of the rung 14a and thus not obstruct close coming together of the legs 10 and 11, that the rung 14a is shown channel-shaped. All of the lugs may of course be made channel-shaped if desired, especially for strength, but the collapsible ladder as disclosed herein and defined in the appended claims will function whether or not any or all of the rungs are flat or channel-shaped.

What is claimed is as follows:

1. A collapsible ladder consisting of two upright legs and a plurality of equidistantly spaced rungs pivotally attached to said legs, said rungs including straight body portions and end deformations extending from said body portions beyond the pivot axes thereof and normally engaging said legs and constraining the rungs from swinging in one direction about their pivots while permitting swinging of the rungs in the opposite direction, one of said rungs above the bottommost rung having pivoted locking means suspended from one end thereof engageable with the corresponding end of the next lower rung for releasably blocking said next lower rung from swinging in said opposite direction.

2. A collapsible ladder according to claim 1, said deformations which are positioned adjacent one of said legs comprising noses extending downward at right angles to said body portions and said deformations which are positioned adjacent the other of said legs comprising noses extending upward at right angles to said body portions, said locking means being suspended from that end of said one of said rungs which has the nose thereon extending upward from the body portion thereof, said locking means comprising a lug having a length such that when the ladder is in extended condition the lower end of the lug

engages the upper end of the corresponding upwardly extending nose on said next lower rung.

3. A collapsible ladder according to claim 2, said legs being channel-shaped in cross-section and positioned with the open channels facing toward each other, said rungs having a width less than the width of said channels, means for pivotally attaching said rungs to said legs as aforesaid consisting of pivot pins supported in the opposed wings of said channel-shaped legs whereby when the ladder is in collapsed condition said rungs are contained partly within the channel of each leg.

4. A collapsible ladder according to claim 3, said one of said rungs being channel-shaped in cross-section throughout the length thereof, said lug having a width

less than the width of the channel of said one of said rungs whereby said lug is registerable within said last-named channel when the ladder is collapsed.
